UNITED STATES PATENT OFFICE.

MATTHEW MORRIS, OF NORWICH, CONNECTICUT, ASSIGNOR TO THE NORWICH WOOLEN MILLS COMPANY, OF NORWICH, CONNECTICUT, A CORPORATION OF CONNECTICUT.

MEASURING DEVICE.

1,308,295.

Specification of Letters Patent.

Patented July 1, 1919.

Application filed July 29, 1918. Serial No. 247,233.

To all whom it may concern:

Be it known that I, MATTHEW MORRIS, a citizen of the United States, residing at Norwich, county of New London, State of Connecticut, have invented certain new and useful Improvements in Measuring Devices, of which the following is a specification.

This invention relates more especially to devices for measuring the amount of goods passing through or from a machine or produced by a machine. The primary object of my invention is to provide an improved construction, combination and arrangement of parts in a device of this character, whereby the amount of movement or production of goods may be accurately measured, and an undue waste of goods avoided. Certain features of this device which are hereinafter explained, reside in simple and effective means for accurately predetermining the extent of goods to be produced by or passed through the machine, thus making it unnecessary to uselessly prolong the operation of said machine after the desired result has been obtained. One object of the present invention is to provide improved means for registering predetermined amounts of goods which are being moved or produced by a machine. Another object is to provide improved means for cutting out the power or interrupting the movement or production of goods. Other and further objects will appear in the specification and be pointed out in the appended claims, reference being had to the accompanying drawings which exemplify my invention in a preferred embodiment. In these drawings, the invention is illustrated in an adaptation to a circular knitting machine which operates the measuring device, preferably, by causing the goods or product to pass over an instrumentality, such for example, as a wheel for imparting a relative movement to an indicator and scale by means of which the amount of movement or production is to be measured. In the drawings:

Figure 1 is a top plan of one embodiment of my invention, in this instance attached to a circular knitting machine;

Fig. 2 is a front elevation of the same, on an enlarged scale, as said embodiment is seen when viewed from the outer periphery of the knitting machine looking toward the center.

Fig. 3 is an enlarged section on the line

3—3, Fig. 1, parts being shown in elevation;

Fig. 4 is an enlarged section on the line 4—4, Fig. 1, parts being shown in elevation;

Fig. 5 is a side elevation of another embodiment, parts being shown in section;

Fig. 6 is a top plan view of the same.

According to the embodiment of my invention shown in Figs. 1, 2, 3 and 4, a bracket 1 is suitably secured to the rotary frame or traveling ring 2 of a circular knitting machine (see Figs. 3 and 4). The ring 2 is provided with a circular rack 3 with which meshes a driving gear 4 mounted on a power shaft 5 which may be the main drive shaft of the knitting machine. The knitting machine parts shown on the drawings are fragments of a well known type of knitting machine which is usually provided with a slidable ring 6 which controls the application of power to the knitting machine by shifting a belt from a tight to a loose pulley or vice versa. Usually, in a circular knitting machine the ring 6 is shifted by hand or by means of an automatic cut-out device which depends for its operation on the uninterrupted supply of yarn, or on conditions around the knitting needles. According to the present embodiment of my invention, the bracket 1 is provided with a laterally projecting portion 7 with an upwardly deflected extremity 8 which carries an adjustable scale bar 9. As shown best in Fig. 2, the bracket 1 carries a stud 10 which is secured in said bracket by means of a nut 11. Journalled on the stud 10 is a wheel 12 provided with radially projecting pins 13 which are adapted to be engaged by the goods 14 which in this instance are drawn from the knitting machine. Secured to the lateral face of wheel 12 is a strap or band 14^a which carries a screw 15, said screw being rigidly secured to the strap or band 14^a by means of check nuts 16. An indicator arm 17 which is adapted to coöperate with the scale bar 9 to indicate the amount of goods passed over the wheel 12, is provided with a hub comprising split nut sections 18 and 19, the former being integrally formed with the indicator arm 17 while the latter is yieldably connected thereto by means of springs 20 which are interposed between the cap section 19 and the heads of a pair of studs 21 which pass through the cap 19 and

are threaded into the part 18 of the indicator arm. The purpose of this yieldable pressure between the nut sections and the feed screw 15 is to adapt said feed screw to gradually move the arm 17 into position to actuate a stop or cut-out mechanism after the indicator is released from engagement with the scale bar. Coöperating with this feature of the device, is an abutment nut 22 which 5 is split on one side of the feed screw 15 and provided with a set screw 23 by means of which it may be rigidly secured to said feed screw 15. At the same time, it may be adjusted to any desired position corresponding to the setting of the scale bar 9 so that the indicator arm 17 will be gradually moved to dotted line position shown in Fig. 4 by coming into abutment with the nut 22 which prevents its further progress along 10 the feed screw. The abutment nut 22 in conjunction with feed screw 15 therefore constitutes positively acting means for forcing the indicator arm 17 to revolve on said feed screw should its grip on the screw be insufficient for that purpose. Referring now 15 to Fig. 4, a pin or post 24 is provided with a reduced end 25 which is threaded into the traveling ring 2 and at the same time serves to secure the bracket 1 in position on said ring. Depending from the bracket 1 is an arm 26 which carries a pin 27 on which oscillates a latching dog 28 provided with a nose 29 which is adapted to engage in a recess 30 in the lower end of a sleeve 31 which 20 reciprocates on the post 24 and is provided with a slot 32 by means of which its endwise movement is limited with reference to a pin 33 which projects laterally from the post 24. As the traveling ring 2 revolves 25 on its axis, the sleeve 31 is retained in its raised position by means of the latch dog 28, until such time as the indicator arm 17 has been fed into a position beyond the right hand extremity of scale bar 9, according 30 to Fig. 2, when it becomes elevated into dotted line position, shown in Fig. 4, to engage the latch dog 28, thus serving to withdraw the nose 29 from the recess 30. Immediately the sleeve 31 falls to its lower 35 position and during the course of the succeeding revolution of the ring 2, said sleeve 31 will come into engagement with the inwardly projecting arm of a lever 34 which is pivotally mounted on a post 35 carried 40 by a fixed plate or frame 36 of the machine. The outer end of the lever 34 is provided with a handle 37 by means of which it may be hand operated when desired. The inner arm 34 of said lever is provided with a 45 slot 38 through which projects a pin or bolt 39 carried by the slidable ring 6, which, as hereinbefore stated, is adapted by its movement to bring the machine to a stop.

Referring now to the embodiment of my 50 invention shown in Figs. 5 and 6 in order to

adapt this attachment for a knitting machine of small radius, or for any other machine in which the arrangement shown in Figs. 1 to 4 inclusive is not adapted, the traveling ring 40 provided with circular rack 41 carries a 70 bracket 42 upon which is journaled a wheel 43 provided with radial pins 44 which may be engaged by the goods or machine product for rotation in the direction of the arrow shown in Fig. 5. Rotating with the wheel 75 43 is a bevel gear 45 which meshes with a second bevel gear 46 keyed to the upper end of a feed screw 47 which is journaled in a bearing 48 and supported vertically by means of a collar 49. On the lower end of 80 the feed screw 47 is an adjustable abutment 50 which may be set to any desired position to limit the downward movement of the indicator nut 51 which slidably engages a scale rod 52 which is adjustably mounted in a 85 socket 53 which is preferably rigidly connected to the bearing 48. The operation of this modification is somewhat similar to the first embodiment, and is as follows:

As the goods or product are passed from 90 the machine, they engage the wheel 43 and thus serve to rotate the feed screw 47. The indicator nut 51, as it moves upwardly, indicates its travel on the scale bar 52. Eventually it is brought into engagement with lever 95 54 which is pivoted at 55 within a lug 56 carried by the bracket 42. The lever arm 54 is provided with a nose or shoulder 57 adapted to engage in the recess 58 in a sleeve 59 and reciprocates on a post 60, being limited in its movement by means of a pin 61 carried by the post 60 and which slides in a slot 62 in the sleeve 59. It will be understood from this description that as the indicator nut 51 nears the upper end of its movement, the parts assume relative positions shown in dotted lines in Fig. 5, which releases the sleeve 59. Whenever the sleeve 59 is released it drops into position to come into engagement with the cut-out lever 63 which 100 is pivoted on the post 64 and operates a pin or bolt 65 carried by a slidable ring 66 which stops the machine. As shown in Figs. 5 and 6, the invention is particularly adapted for attachment to machines having small lateral 105 extent.

The operation of my improved measuring device is substantially the same for both embodiments. Thus, as the finished product, such as the knitted goods in Figs. 1 and 2, passes from the machine, the wheel 12 or 43 is rotated thereby and imparts this rotary movement to feed screw 15 or feed screw 47 as the case may be. The movement of either of these feed screws 15 or 47, eventually causes the indicator 17 or 51 to displace the latch which in turn permits the sleeve 31 or 59 to drop so that its new path of movement brings it into engagement with the lever 37 or 63 which imparts the belt shifting move- 115 120 125 130

ment to the ring 6 or 66 and stops the machine.

I claim:—

1. In a device of the character described, 5 an instrumentality having means to move it proportionately to the movement of goods to be measured, an indicator moved by said instrumentality, graduated means carried by said device for determining the extent of 10 movement of said indicator, and cut-out means operated by said indicator by means of the movement imparted to it by said instrumentality after having completed its graduated movement.
- 15 2. In a device of the character described, an instrumentality having means to move it proportionately to the movement of goods to be measured, means including an indicator for predetermining the extent of movement 20 of said instrumentality, and a cut-out instrumentality operated by said predetermining means at the conclusion of such movement.
- 25 3. In a device of the character described, 25 an instrumentality movable by engagement with goods to be measured, a graduated element, an indicator element, said elements being in slidable engagement with each other during a portion of the movement of said instrumentality and one of said elements being released to a movement different from said sliding movement at the end of said slidable engagement, said instrumentality imparting relative movement to said graduated and indicator elements and the later different movement to one of said elements, and cut-out means operated by the last mentioned element.
- 35 4. In a device of the character described, 40 a graduated scale, an indicator movable relatively to said scale, a feed shaft for moving said indicator, means for operating said feed shaft, said means including an instrumentality movable in amounts proportional 45 to the movement for production of goods to be measured, and cut-out means suitably arranged to be operated by said indicator after a predetermined movement of said feed shaft.
- 50 5. In a machine of the character described, 50 a bracket, a wheel journaled in said bracket and adapted on its periphery to be engaged by a fabric or goods to be measured, a feed screw rotated by said wheel, an indicator threaded to said feed screw, and a scale bar mounted in said bracket for holding said indicator against rotation, said scale bar terminating short of said feed screw for releasing said indicator to a movement about 60 the axis of said feed screw.
- 65 6. In a machine of the character described, 65 a bracket, a wheel journaled in said bracket and adapted on its periphery to be engaged by a fabric or goods to be measured, a feed screw rotated by said wheel, an
- 70 indicator threaded to said feed screw, a scale bar mounted in said bracket for measuring the movement of said indicator, means mounted on said feed screw for limiting the axial movement of said indicator along 75 said feed screw and adapting said feed screw to lift said indicator at the end of its axial movement, said indicator being provided with a split nut and means yieldably clamping the parts of said split nut to said feed screw, a stop lever, normally inoperative means for moving said stop lever, and a latch for holding said stop lever moving means inoperative, said latch being suitably disposed to be operated by the lifting 80 movement of said indicator, said stop lever moving means being adapted to become operative when released by said latch.
- 85 7. In a machine of the character described, the combination with a stopping mechanism including an operating lever and a latch for controlling the actuation of said lever, of means operated by the movement of the product of said machine for measuring the amount of such product, said means 90 being adapted by a predetermined amount of movement to operate said latch.
- 95 8. In a machine of the character described, a movable frame, an instrumentality partaking of the movement of said frame, 95 said instrumentality being constructed and arranged to have a measuring movement imparted thereto by the goods produced by said machine, means for registering the extent of the measuring movement, and means 100 carried by the movable frame and adapted to be operated by said registering means after a predetermined movement of said registering means for stopping the operation of said machine.
- 105 9. In a machine of the character described, a revolving frame, a bracket carried thereby, a wheel journaled in said bracket and adapted to be rotated by goods produced by said machine, an indicator 110 moved by said wheel, a scale for measuring the movement of said indicator, a lever for stopping said machine, and means carried by said revolving frame and adapted to be controlled by said indicator for operating 115 said stopping lever.
- 120 10. In a machine of the character described, a revolving frame, a bracket carried thereby, a wheel journaled in said bracket and adapted to be rotated by goods 120 produced by said machine, an indicator moved by said wheel, a scale for measuring the movement of said indicator, a lever for stopping said machine, and means carried by said revolving frame and adapted to be 125 operated by said indicator for moving said stopping lever, said scale holding said indicator from its machine stopping movement during a portion of its measuring movement.
- 130

11. In a machine of the character described, a traveling ring, a bracket carried by said ring, a wheel journaled in said bracket and adapted to be rotated by goods produced by said machine, a feed screw rotated by said wheel, an indicator threaded on said feed screw, a stop for limiting the movement of said indicator along said feed screw, said indicator being thereby forced to revolve about the axis of said feed screw after its movement along the feed screw, and cut-out means operated by the revolving movement of said indicator.
12. In a machine of the character described, a traveling ring, a bracket carried by said ring, a wheel journaled in said bracket and adapted to be rotated by goods produced by said machine, a feed screw rotated by said wheel, an indicator threaded on said feed screw, a stop for limiting the movement of said indicator along said feed screw, said indicator being thereby forced to revolve about the axis of said feed screw after its movement along the feed screw, and cut-out means operated by the revolving movement of said indicator, and a scale bar carried by said bracket and slidably engaging said indicator substantially throughout its movement along said feed screw.

MATTHEW MORRIS.
